78

UNITED STATES PATENT OFFICE.

JAMES R. FLOYD, OF NEW YORK, N. Y.

IMPROVEMENT IN MAKING BURGLAR-PROOF SAFES.

Specification forming part of Letters Patent No. 30,398, dated October 16, 1860.

T73
To all whom it may concern:

Be it known that I, JAMES R. FLOYD, of the city, county, and State of New York, have invented certain new and useful improvements in the manufacture of burglar-proof safes by the employment of a material which cannot be drilled or broken into; and I do hereby declare and ascertain my said invention.

Heretofore many attempts have been made to construct a safe of iron which could not be drilled or broken into, but, as yet, without success. Of this character is the safe of Lilley; but this safe can be readily drilled and blown open, and does not afford that entire protection which by my discovery I have succeeded in giving to such a structure. I form a safe of cast metal; but, as its figure and dimensions are optional and well known, I make no claim to that, nor does it form any portion of my invention or discovery. Hence I make no drawings of any particular-shaped safe, but leave that to the taste of the constructor. The material which I use, and which I have discovered

is alone capable of entirely resisting the drill, is the iron obtained from "franklinite," or the zinc ores of New Jersey, and iron of other similar constitution of other localities, which is a peculiar crystallized metal that a steel tool cannot be made to successfully attack. Consequently I have discovered that by the employment of this metal in forming cast-metal safes I make them simple and comparatively cheap and render them completely burglar-proof.

What I claim as my invention or discovery is—

The employment of the above - described franklinite or other similarly-constituted metal in forming cast-metal safes, substantially as and for the purposes set forth.

In testimony whereof I have hereto set my hand.

JAMES R. FLOYD.

In presence of—

JOHN FARREL,
J. J. GREENOUGH.
